UNITED STATES PATENT OFFICE

FRANK A. FAHRENWALD, OF CHICAGO, ILLINOIS

FURNACE CONVEYER SHAFT WITH DISKS

Application filed September 29, 1930. Serial No. 485,279.

This invention relates to a novel construction of shaft for use in heat treatment furnaces, for instance, sheet steel normalizing furnaces, and particularly a shaft upon which are mounted work supporting disks or the like. The invention also relates to a novel construction of means whereby the disks are held in assembly with and receive their drive from the shaft. The invention also relates to a novel combination of shaft and disks which avoids deteriorating stresses in the members under heat expansion; also to a novel combination of shaft disk and interlocking means whereby the disks are positioned upon the shaft and driven by the shaft.

Among the problems to be met in providing and maintaining in operative condition the work supporting and feeding shaft in a heat treatment furnace are the establishment of a relation of structural strength to weight sustained in the shaft that will avoid distortion or letting down of the portion of the shaft within the high temperature area of the furnace, while the shaft is being supported by its ends in bearings located outside the walls of the furnace; the avoidance of checking or cracking of the shaft under heat expansion; the avoidance of undue cooling of the furnace chamber and the sheets or other workpieces by conduction of heat through the work supporting disks and the shaft; the provision for convenient assembly of the disks with and in driven relation to the shaft as well as their ready disassembly and replacement when necessary; and the avoidance of undue constriction of the shaft by the surrounding disk when the shaft expands under heat. Since it is generally preferred to resort to foundry methods of production of shafts for the purpose stated, it is also desirable to have a construction of shaft which will facilitate coring, proper distribution of the metal in pouring, avoidance of checking and cracking in cooling, and facility for dressing and thereby providing accurate alignment of disk-seats upon the shaft without having to straighten the shaft or dress its surface as a whole, in insuring a level sheet support across the tops of all the disks when in use.

Accordingly, the present invention contemplates a shaft for metallurgical furnaces, or the combination of such a shaft and work-supporting disks surrounding and held in driving relation upon the shaft, embodying 55 individually, collectively, or in various combinations, as hereinafter pointed out in the claims, structural characteristics substantially as follows. A relatively large hollow body portion with comparatively thin walls, 60 made of an alloy which bestows upon the shaft capacity to retain its shape when supported by its ends (preferably of relatively smaller diameter) resting in bearings outside of the furnace and while the enlarged 65 portion of the shaft is subjected to temperatures of the order of 1800 to 2000° F. without the assistance of cooling influences such as air or water flowing through the shaft; this shaft being constructed with a series of 70 axially spaced seats upon which to mount surrounding work-supporting disks, each seat consisting of a series of circumferentially spaced elevations on the surface of the shaft, so that in insuring coaxial alignment 75 of the disks upon the shaft, correction of unavoidable distortion in the cylindrical casting will involve merely the dressing (e. g. by grinding) of the faces of the elevations 80 rather than correcting the whole surface of the shaft, and so that the disk when in position may, if desired, remain out of contact with substantial areas of the shaft between its surface elevations; the elevations upon which 85 the disks seat constituting means through which the shaft drives the disks, to which end, provision is made for interlocking each disk with one or more of the elevations in the direction of drive; the interlocking means 90 being also made to serve, if desired, as the means for preventing displacement of the disk from its seat and being preferably made conveniently releasable to permit replacement of disks; the elevations being developed 95 by deflection of the wall of the shaft without materially changing the thickness of the metal at an elevation, as distinguished from developing elevations or protuberances by local enlargement of the mass or thickness 100 of the wall, and these elevations, or some of

them, being slotted in the direction of the axis of the shaft as a safeguard against setting up strains under high heat expansion; and the several elements of the combination embodying structural details which adapt them to advantageously enter into the functional and cooperative relationships described.

In the accompanying drawings—

Figure 1 is a vertical section of a conventional type of heat treating furnace, with a shaft constructed and equipped with disks in accordance with the present invention; disks located by another shaft in rear of the shaft shown being illustrated in positions alternating with the disks on the shaft shown.

Figure 2 is a horizontal section through portions of the two side walls of the furnace shown in Figure 1, in the plane of the shaft, and showing in axial sections two adjacent shafts together with disks mounted thereon.

Figure 3 shows in side elevation one of the disks employed in Figures 1 and 2, and in transverse section in the plane of the disk, the shaft upon which the disk is mounted together with one form of interlocking and driving connection between the disk and the shaft.

Figure 4 shows a shaft in section as in Figure 3, together with a fragmentary portion of the disk, and a modified construction of interlocking and driving means.

Figure 5 is a section on the line 5x—5x of Figure 3, showing the means for interlocking the disk with and imparting its drive from the shaft.

Figure 6 is an axial section of a portion of a shaft and disks mounted thereon through means of raised seats upon the shaft, and a modified construction of releasable bayonet joint.

Figure 7 is a transverse section on the line 7x—7x of Figure 6;

Figure 8 is an axial section of a portion of a shaft and disks mounted thereon, showing still another means for interlocking the disks against displacement and transmitting their drive from the shaft; and

Figure 9 is a section on the line 9x—9x of Figure 8.

In Figures 1 and 2, A, B and C represent side, bottom and top walls typical of a known construction of heat treating furnace. 1 represents shafts mounted so that their main body portions will rotate within the furnace, for instance, by having their reduced ends extending through the furnace walls and supported in bearings external thereto. 2 represents disks mounted upon the shaft in a relation which adapts them to afford support to a sheet of steel or other material that is to be heat treated in the furnace. These disks are constructed with rims 3, webs 4 and hubs 5, according to the particular construction of disk here selected for purposes of illustration, which construction is that of co-

pending application Serial No. 326,513, now Patent No. 1,780,018.

For purposes of illustration, the several features of the present invention are illustrated in connection with a shaft 1 which is usually constructed of some suitable alloy which bestows upon it the capacity of retaining its shape when supported by its ends in external bearings as shown, and while its intermediate or body portion is subjected to the relatively high temperatures under which the furnace is worked, and which, in order that it will stand up under these conditions, has its body portion made of relatively large diameter, hollow, and with relatively thin walls, while the supporting ends are of materially smaller diameter and merge with the enlarged body portion after the manner of a bottle-neck; this construction being found also to reduce heat losses by conduction and convection, particularly when the shaft is of the non-cooled type. It is to be understood that the invention is applicable to shafts of other construction, and even shafts in connection with which a conduit is used for the purpose of passing a cooling medium through the shaft.

Referring to Figures 1 to 3 inclusive, shaft 1 is provided with elevations 6 adapted to receive the hubs 5 of the disks 2, some of which elevations are provided with slots 7 extending in the direction of the axis of the shaft for the purpose of subdividing the circumference and interrupting stresses that might otherwise be set up under high heat expansion; and these slots 7 may extend longitudinally beyond the elevations, if desired, to insure this effect. The elevations 6 are circumferentially interrupted in order to leave between them a series of recesses 8 in the circumferential direction of the shaft, over which recesses a disk, mounted upon a given series of elevations, will remain out of contact with the shaft as a further safeguard against setting up of undesirable stresses, for instance, stresses due to resistance of the disk to circumferential expansion of the shaft. Additional advantages arise from the use of elevations upon which to mount the disks, among which are greater convenience in providing dressed surfaces upon which to seat the disks, and greater convenience in moving the disks to their seats upon the elevations.

An important feature of the preferred embodiment of the present invention consists in developing (for instance, by appropriate shaping of the core in casting) the elevations 6 as deflections in the wall of the shaft, as distinguished from massive protuberances developed by mere increase of thickness of the walls where the elevations are required and the change from one level to the other is without abrupt angle. This condition further contributes to the avoidance of unde-

sired stresses under changes of dimension incident to changes in temperature.

Another important feature of the preferred embodiment of the present invention 5 consists in the use of one or more of the elevations upon which a disk seats to transmit drive from the shaft to the disk. To this end, according to Figures 2 and 3, one or more of the elevations 6a, instead of being 10 slotted as at 7 in the elevations 6, are constructed to serve as driving elevations. For instance, with the hub 5 of disk 2 constructed with a stud housing 9 recessed as at 10 to receive a stud 11, it is merely necessary to 15 perforate the elevation 6a as shown at 11a to admit the shank of said stud, in order to establish an efficient drive between an elevation and a disk. And in order to render convenient the assembly of the disk into such 20 driving relation, the recess 10, as shown in Figures 3 and 5, may be of bayonet joint type and provided with a gate 12 through which the stud 11 may enter by axial relative movement between the disk and the shaft, the gate 25 12, after assembly, being closed by filler pin 13 releasably held in place by slitting its end 14 after the manner of a cotter pin. Thus, in assembling the disk with the shaft, in addition to seating the disk upon the elevations of the shaft, the driving connection 30 between an elevation and the disk is established by merely dropping stud 11 in a recess 11a, then sliding the disk axially until the stud 11 arrives opposite the recess 10, then 35 imparting a slight rotary movement to the disk, and finally inserting and clinching the filler pin 13.

According to Figure 4, driving interlock 40 between the disk and the shaft is established at two diametrically opposite elevations 6a by inserting the through pin 11a in two holes 11a and then working the bayonet joint assembly as described, the single filler pin 13 being sufficient to prevent counter-rotation 45 that would release the interlock.

According to Figures 6 and 7, the bayonet joint stud 15 is carried by the hub 5a of the disk 2a; and this stud, after entering a slot 7a extending through an elevation 6, may be 50 shifted into a bayonet joint pocket 16 in said elevation, and there confined against displacement by means of a cotter pin 17 inserted into the slot 7a, so that in this instance the slotted elevation 6 becomes the driving 55 elevation.

According to Figures 8 and 9, the slot 7 is made an element of the interlock by providing each disk hub 5b with a key-lug 18 that slides into one of the slots 7 as the disk 60 is brought to its seat, and the disks are prevented from sliding axially out of the resultant driving interlock by means of end rings 20 secured by screws 21 and intermediate spacing strips 19, the ends of which 65 enter the slots 7 of the elevations 6 and into

abutment with the lugs 18, and are there held by the overlapping portions of the hubs 5b so that here again the elevations serve not only as disk seating means but as disk driving means.

It is to be noted that in the form shown in Figures 6 and 7, where the bayonet joint studs are carried by the disks, as well as the form shown in Figures 8 and 9, each disk will be able to pass antecedent disks in reaching its own seat, since the driving projections which the disks carry can pass completely through a slot if necessary, or pass between two elevations until it reaches the circumferential series of elevations which are to serve as its own seat, when its driving projection will be passed into the slot which is to interlock it with its own driving elevation. In Figure 6 the slotted elevations will be alternated in position instead of being in alignment as in Figure 8, but it will merely be necessary, in passing one elevation to reach another, to move the disk axially until its bayonet joint stud 16 passes a slot, then rotate it 90° until it comes opposite the next slot, and so on until it reaches its own seat.

I claim:

1. A shaft for supporting workpieces within a heat treatment furnace, said shaft consisting of a cylindrical body portion constructed with a relatively thin wall and having upon the exterior of its wall integral seating elevations; the thickness of the wall at such seating elevations being not materially greater than that of the main portion of the wall.

2. In combination with the shaft described in claim 1, a work-supporting disk seated upon a plurality of the elevations of said shaft, and means interconnecting said disk with at least one of said elevations and transmitting rotary drive from the shaft to the disk.

3. A hollow shaft for heat treatment furnaces, constructed with relatively thin walls and having its said walls deflected radially outward at a plurality of circumferentially spaced places providing an annular series of disk seating elevations; said walls at the places of said elevations being approximately uniform in thickness with other portions of the walls.

4. A hollow shaft for heat treatment furnaces as described in claim 3, in which the disk seating elevations are arranged in a plurality of circumferential series, with portions of the main cylindrical surface of the shaft alternating with the elevations of each series and also with the several series of elevations.

5. A hollow shaft for heat treatment furnaces as described in claim 3, in which at least one of the elevations is slotted longitudinally of the shaft to receive drive-transmitting means carried by a disk.

6. A hollow shaft for heat treatment furnaces as described in claim 3, in which at least one of the elevations is slotted longitudinally of the shaft to receive drive-transmitting means carried by a disk; said slot extending through said elevation in the direction of the axis of the shaft.
- 5 7. A shaft for heat treatment furnaces as described in claim 3, in which the circumferential series of elevations is repeated at intervals in the axial direction of the shaft, and said shaft has mounted upon each circumferential series of elevations a sheet supporting disk; the several disks and seating elevations 10 being constructed to permit a disk, in reaching the series of elevations upon which it is mounted, to pass the elevations of antecedent circumferential series.
- 15 8. A conveying shaft for heat treatment furnaces, constructed with a relatively large-diameter, thin walled body portion, which said wall is radially deflected to provide external surface elevations at selected positions without materially varying the thickness of 20 the wall.
- 25 9. A conveying shaft for heat treatment furnaces, constructed with a relatively large-diameter, thin walled body portion, which said wall is radially deflected to provide external surface elevations at selected positions 30 without materially varying the thickness of the wall; said elevations extending but a fraction of the circumferential dimensions of the shaft, and leaving relatively low intervening portions of the shaft in circumferential series with them; said shaft also having in its wall slots extending at a substantial angle to its circumference; and said 35 slots extending through said elevations.
- 40 40 Signed at Chicago, Illinois, this 24th day of September, 1930.
